UNITED STATES PATENT OFFICE

90,405

DESIGN FOR A COMBINED VOTING MACHINE CABINET AND BOOTH

Arthur F. Foehrenbach, Canton, Ohio

Application April 25, 1933. Serial No. 47,895

Term of patent 14 years

To all whom it may concern:

Be it known that I, ARTHUR F. FOEHRENBACH, a citizen of the United States, residing at Canton, in the county of Stark and State of Ohio, have invented a new, original, and ornamental Design for a Combined Voting Machine Cabinet and Booth, of which the following is a specification, reference being had to the accompanying drawings, forming part thereof.

Fig. 1 is a perspective view of a voting machine cabinet in closed position showing my new design.

Fig. 2 is a perspective view thereof illustrating the doors in open position forming the voting booth.

Fig. 3 is a perspective view thereof with the doors in open position, illustrating the party panels.

I claim:

The ornamental design for a combined voting machine cabinet and booth as shown.

ARTHUR F. FOEHRENBACH.
